UNITED STATES PATENT OFFICE.

JOSEPH M. S. KING AND ROSS S. LUND, OF SALT LAKE CITY, UTAH, ASSIGNORS TO UTAH RADIO PRODUCTS COMPANY, OF SALT LAKE CITY, UTAH, A CORPORATION OF UTAH.

ELECTROMAGNETIC VIBRATORY UNIT.

Application filed January 14, 1926. Serial No. 81,348.

This invention relates to an improved electromagnetic vibrating unit, and its principal objects are to provide a device which shall:

- 5 First. Be extremely simple.
- Second. Be arranged with the utmost regard for economical production.
- Third. Employ the magnetic flux in an efficient manner: that is, reduce the leakage

10 losses to a minimum.

Fourth. Be sturdy and durable in service.

The competitive conditions in the field which this instrument serves, have made it necessary to take recognition of the utmost 15 possible economies of manufacture and production.

Therefore, in attaining the objects previously outlined, we have, in our present invention, endeavored to take advantage of 20 every avenue that seemed to offer any possibilities for lessening costs, while at the same time maintaining a high standard of quality and performance in the finished instrument.

25 To this end we have simplified our instrument, first, where the economy of labor and material entering into each individual part is concerned, and second, where the assembling of the individual parts into the 30 finished combination is concerned.

Our invention is not intended to be revolutionary in its general character, but merely, to achieve the desired end in the most direct and economical manner.

35 The features for which the protection of letters patent is desired, are collectively grouped in the claims which conclude this specification.

In the drawing, which represents one embodiment of our invention:

Fig. 1 is a plan, the usual casing and other incidentals being omitted;

Fig. 2, a front elevation; and

Fig. 3, a longitudinal, vertical center section.

Fig. 4, a transverse vertical section taken on the center line of the electromagnet.

Referring to the drawing, 10 indicates a permanent magnet of plain horseshoe form, the simple construction of which is at once apparent, there being no offset portions, nor complicated parts of any description to cause excessive production costs. All that is necessary, is to bend a steel bar to the simple 55 U-shape, and to form two holes for the re-

ception of the clamping studs 12 and 12-1 near the ends of the legs 10-1 and 10-2, of the U. It will be seen that the magnet may be made of a generous size, the cross-section of the bar being preferably of substantial uniformity throughout, thus maintaining the width and depth of the original bar and resulting in ends which are neither offset to lie in different planes, nor diagonally disposed and spaced apart in two planes, as in other devices of which we are aware, but on the contrary, are non-offset to lie in the same planes. Offsetting the ends of the magnet adds materially to the expense of production, and instead of improving the magnetic conditions, actually impairs the most efficient action of the magnetic flux by establishing additional poles at the offset portions of the magnets, thus uselessly diverting part of the flux.

The spool 14 of the electromagnet is of such size that it may be clasped exactly within the opening between the legs of the U, these being preferably parallel to each other as indicated in Figs. 1 and 2, where the length of the spool is equal to the inside distance between the magnet legs, and the height of the spool is equal to the height of the magnet bar, the height being determined by the perpendicular distance between two mutually parallel planes defining the principal faces of the permanent magnet. The two pole pieces 15 and 25 may be exactly 80 alike and have the rearwardly extending lugs 15-1 and 25-1, as well as the forwardly inclined side flanges 15-2 and 25-2. A cross-section taken through the pole pieces 15 and 25 within the compass of the side flanges, shows the section of each pole piece to have, in general, a back portion

85 from which the above mentioned side flanges depend, as indicated in Fig. 3. Inasmuch as the inner faces of the lugs 15-1 and 15-2 lie in the same plane with the inner faces of the said back portions, and further, that the flanges are spaced apart from each other substantially the same distance as the width of the spool overall, it is obvious that the spool is securely held in place without the necessity of any other fastening means. 90

In Fig. 2, it will be seen that the side flanges 15-2 and 25-2, of the pole pieces, extend toward each other from their junction with the lugs 15-1 and 25-1 respectively, thus lying virtually in a band, in this 105

- instance comparatively broad, extending obliquely across the end projection, or front, of the permanent magnet and of course, also, obliquely across the flange area of the spool.
- 5 The respective pole-faces, adjacent each other, are spaced apart sufficiently to form the usual gap for accommodating the extremities of the armature 16. The armature may be centrally pivoted as at 16-1, and to 10 one side of the armature may be connected in the usual manner, a tie 17 extending to a diaphragm of ordinary construction (not shown), or to any other desired vibratory element.
- 15 The assemblage thus far described, may be mounted upon any suitable base such as the ring 18, and be fastened by threading the clamping studs 12 and 12-1 therein, as clearly shown in Fig. 4, the stud 12 being 20 arranged to clamp the magnet against the intervening lug 25-1, while the stud 12-1 clamps the magnet against the intervening washer 19.
- In emphasizing the simplicity of construction of this instrument, it is to be noted that, (a) the magnet and spool are both perfectly plain without any special fastening members whatsoever; (b) the pole pieces are extremely simple and may be produced as plain stampings; (c) in assembling, the pole pieces are held spaced apart from each other to a precise gauge, upon the mutually opposed faces of the legs of the magnet, while the spool holding the coil of 25 the electromagnet is most securely clasped in the three principal directions as specified following: longitudinally, by the legs of the magnet; sideways by fitting in closely between the flanges 15-2 of the pole pieces; and vertically, by fitting in closely between the inner faces of the backs of the pole pieces 15 and 25.
- The advantage of the diagonal band construction of the pole-piece flanges, consists in the fact that the leakage of the magnetic flux across the space between the legs 10-1 and 10-2 of the permanent magnet, and respectively, the end faces 25-3 and 15-3 of the pole-pieces (Fig. 2), is reduced to a minimum.
- If the end faces of the flanges 15-2 and 25-2, were to extend vertically from the edges of the armature, then the faces 15-3 and 25-3 would be considerably nearer to the legs of the permanent magnet, thereby increasing very materially the leakage losses in the magnetic flux.
- While a specific embodiment of this invention is herein shown and described, all the detailed parts may, or may not, be in the preferred forms, and further, the preferred forms may be varied from time to time as the development of the invention and the arts to which it appertains, progress. Therefore, that which forms an essential part of this invention will be discernible from the claims in which its spirit is generalized.
- Having fully described our invention, what we claim is:
1. A U-shaped permanent magnet, a coil having a spool held in position along its longitudinal dimension by the legs of said magnet, the height of said spool being substantially equal to the perpendicular distance between the two principal planes of the said magnet, pole pieces having surfaces lying substantially in the said planes, said pole pieces being thereby precisely spaced apart to define a gap between them, the said spool being held against vertical displacement by bearing against the said surfaces of the pole pieces, the pole pieces further, having side flanges defined by parallel edges extending obliquely across the flange area of the said spool, said side flanges being spaced apart from each other to hold the spool against lateral displacement. 75
2. A permanent magnet having legs spaced apart from each other, an electromagnet located between the said legs, and by contact therewith held against displacement along its longitudinal dimension, pole pieces extending inwardly from the two opposing principal planes of the said permanent magnet, said pole pieces having side flanges lying in bands having orthographic projections defined by parallel lines which extend obliquely across the orthographic end projection of the said permanent magnet, said pole pieces being arranged, by contact only, to hold the electromagnet against lateral and vertical displacement. 90
- In testimony whereof, we sign our names hereto.

JOSEPH M. S. KING.
ROSS S. LUND.
